CLAIM

The ornamental design for an eye drop application device as shown and described.

DESCRIPTION

FIG. 1 is an isometric view of an eye drop application device showing our new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is an isometric operational view thereof; and,

FIG. 8 is a rear elevational view thereof showing our design. The container and person each shown in broken lines form no part of the claimed Design.

1 Claim, 6 Drawing Sheets
